No. 835,832.

PATENTED NOV. 13, 1906.

A. M. RICKERD.
MINE DRILL.
APPLICATION FILED JUNE 30, 1906.

UNITED STATES PATENT OFFICE.

ALFRED M. RICKERD, OF RILEY, PENNSYLVANIA.

MINE-DRILL.

No. 835,832.

Specification of Letters Patent.

Patented Nov. 13, 1906.

Application filed June 30, 1906. Serial No. 324,243.

To all whom it may concern:

Be it known that I, ALFRED M. RICKERD, a citizen of the United States of America, residing at Riley, in the county of Allegheny 5 and State of Pennsylvania, have invented certain new and useful Improvements in Mine-Drills, of which the following is a specification, reference being had therein to the accompanying drawings.

10 This invention relates to miners' drills; and its primary object is to provide improved means for supporting a drill in such a manner as to permit it to move within a limited radius.

15 A further object of the invention is to provide novel means for feeding a drill forward and for withdrawing it when desired.

The construction of the improvement will be fully described hereinafter in connection 20 with the accompanying drawings, which form a part of this specification, and its novel features will be particularly set forth in the appended claims.

In the drawings, Figure 1 is a view in perspective of a drill embodying the invention. 25 Fig. 2 is a detail vertical section, on an enlarged scale, of the bit-support. Fig. 3 is a side elevation of a treadle for moving the supporting-frame of the drill. Fig. 4 is a perspective view of the bearing-block for the drill-handle. Fig. 5 is a detail perspective view of a portion of the supporting-frame of the drill; and Fig. 6 is a side elevation, on an enlarged scale, of the point of the drill-bit.

30 The reference numeral 1 designates a base provided with three parallel grooves 2, 3, and 4, serving as a trackway for a drill-supporting frame comprising parallel standards 5, connected at their lower ends by a transverse bar 6 and at points approximately midway of their height by a transverse rod 7. Above the rod 7 each of the standards is formed with an elongated vertically-disposed slot 8, said slots serving as guideways for oppositely-disposed threaded arms 9, projecting from a block 10 arranged between the standards and vertically adjustable therein by means of clamping-nuts 11 fitting the ends of the screw-threaded arms 9 and adapted to 40 frictionally engage the outer sides of the standards. To the lower end of each of the standards 5 is secured a roller 12, mounted in a bracket 13, said rollers being adapted to travel within the grooves 2 and 4 of the base.

55 The block 10 is formed with a central horizontal bore 14, within which is fitted a bush-

ing 15, flared at its outer end. Within the bushing 15 is supported a crank-shaft 16, provided at one end with a handle 17 and having its projecting forward end 18 screw-threaded for the attachment thereto of the rear end of an internally-threaded coupling-sleeve 19, within the forward end of which is fitted the threaded end 20 of a drill-bit 21. Secured to the rear sides of each of the standards 5 is an inclined brace 22, the lower ends of which are recessed to provide tongues 23, fitting the grooves 2 and 4 of the base and adapted to move therein.

The numeral 24 designates a treadle, the forward end of which is pivotally secured upon the rod 7 by bending said end around the rod to form a loop 25. To the under side of the rear end of the treadle is secured a roller-bracket 26, within which is mounted a roller 27, adapted to move within the central groove 3 of the base. The front 28 of the drill is bifurcated, as shown in Fig. 6, to provide two spirally-turned cutters 29.

The utility and operation of the mechanism 80 constructed as thus described will be readily understood. The flared bushing which serves as the bearing for the crank-shaft permits the shaft and the bit coupled thereto to be moved to any point within the radius of 85 the enlarged end of the bearing, and the vertical adjustment of the bit and its operating-crank may be readily effected by means of the threaded arms 9 and the nuts 11. The forward feed of the frame carrying the bit is 90 accomplished by pressure of the foot upon the treadle 24, the rollers on the standards and treadle and the tongues on the lower ends of the braces 22 enabling the frame to be readily moved by the foot of the operator. 95 The bit-coupling facilitates the replacing of bits when required.

What I claim, and desire to secure by Letters Patent, is—

1. A miner's drill comprising a grooved 100 base, a vertically-disposed frame comprising standards movably supported thereon, means for moving said frame, a vertically-adjustable bearing-block supported between the standards of the frame, a flared bushing 105 within said block, and a crank-shaft mounted within said bushing.

2. In a miner's drill the combination with a grooved base, of a movable frame comprising standards having rollers within the 110 grooves and formed with vertically-disposed slots, means for moving said frame upon said

base, a block having oppositely-projecting threaded arms extending through said slots, nuts on said arms for securing said block at different vertical adjustments, a flared bushing 5 extending through said block, a crank-shaft within said bushing, a coupling-sleeve on said shaft, and a bit detachably secured to said sleeve.

3. In a miner's drill the combination with 10 a grooved base, of a drill-supporting frame thereon, comprising parallel standards carrying rollers, and inclined braces secured to said standards and provided with tongues to fit the grooves of the base, and a treadle secured at one end to the frame, and provided 15 with a roller at its opposite end.

4. In a miner's drill the combination with a grooved base, of a frame comprising parallel

standards formed with vertical slots, a connecting cross-bar, and inclined braces provided with guiding-tongues, a block arranged between said standards and having oppositely-extending threaded arms extending through said slots, clamping-nuts on said arms, a bushing within said block, a crank-shaft within said bushing, a drill connected to 20 said shaft, and a treadle pivotally secured at its forward end to a cross-bar of the frame, and carrying a roller at its rear end. 25

In testimony whereof I affix my signature 30 in the presence of two witnesses.

ALFRED M. RICKERD.
